UNITED STATES PATENT OFFICE.

FREDERICK E. KOHLER, OF CANTON, OHIO.

DESIGN FOR AN ANTIRATTLER.

SPECIFICATION forming part of Design No. 26,652, dated February 16, 1897.

Application filed January 2, 1897. Serial No. 617,846. Term of patent 7 years.

To all whom it may concern:

Be it known that I, FREDERICK E. KOHLER, of Canton, Stark county, Ohio, have invented and produced a certain new and useful Design 5 for Antirattlers, of which the following is a specification, reference being had to the accompanying drawings, that form a part of the specification.

Figure I is a view in perspective of the anti-rattler. Fig. II is an edge view of the device. Fig. III is a front side elevation of the same. Fig. IV is an opposite side view of the device. Fig. V is a top plan of the same.

The antirattler consists of two sheet-metal 15 pieces A and B, riveted together at their lower ends at C. Members A and B diverge above the rivets, and side divergence commences at or near the rivets.

The outer member, or antirattler proper, of 20 the device has its upper portion arched inwardly, as shown very clearly in Figs. I and II, and is rounded at the junction of its top and upright or side edges, as shown at a, Figs. I

and III. The inner member, or hanger proper, of the device extends upwardly above the 25 antirattler proper and is bent or flanged laterally, as at b, away from the antirattler proper at its upper end. Said lateral flange of the hanger proper has its edge curved inwardly at the central portion of the flange, as shown 30 at b' in Fig. V, and the flange slopes downwardly from its central portion toward each end, as shown at b².

The leading feature of my design consists in the peculiar bending or curvature of the 35 two members of the device.

What I claim is—

The design for an antirattler, substantially as shown and described.

In testimony whereof I sign this specification, in the presence of two witnesses, this 25th day of November, 1896.

FREDERICK E. KOHLER.
